UNITED STATES PATENT OFFICE

CHARLES F. SCHMELZ, OF BRIDGEPORT, CONNECTICUT, ASSIGNOR TO THE STAY-PUT SHADE ROLLER CORPORATION, OF BRIDGEPORT, CONNECTICUT, A CORPORATION OF CONNECTICUT

SHADE-ROLLER

Application filed July 7, 1930, Serial No. 466,015. Renewed June 20, 1931.

This invention relates to shade-rollers, and more particularly to mechanism whereby the rotation of the roller in opposite directions, to raise or lower shade, is controlled and it has for its object the provision of an improved device of this character whereby the rotation of the roller in one direction will be frictionally resisted, while, when the roller is being rotated in the other direction, the frictional resistance is automatically and materially relieved.

The invention has been clearly illustrated in the accompanying drawings, in which similar characters denote similar parts and in which

Figure 1 is a front view of a shade roller with its supporting brackets, the latter being shown in central section. Fig. 2 is a rear face view of the base plate. Fig. 3 is a side-face view of the supporting bracket which carries the operating mechanism. Fig. 4 is an end view of the shade-roller per se and Fig. 5 shows, in perspective view, the several elements alined in sequential positions ready to be assembled.

Briefly stated, the present invention provides an improved mechanism whereby a solid and spring-less shade roller which may be coupled thereto, will firstly be frictionally held against being rotated by the weight of the down-hanging portion of the shade-fabric and its lower stick and tassel, and which will, secondly relieve this friction when a cord attached to the main pulley or spool of the mechanism is pulled to rotate the roller in the opposite direction, to raise the shade, so that the operator's hand-pull has to overcome only the weight of the down-hanging portion of the shade.

Referring to the drawings, the operating mechanism of the roller comprises a stationary support formed in the shape of a base-plate P consisting substantially of a disk 10 having a central hollow hub 11 and attaching-prongs 12 adapted to be driven into the inner side face of a window casing, the several portions of the base plate being preferably homogeneous and formed from sheet-metal by punching and drawing-process. Mounted for free rotation on the hub 11, is the main

pulley or spool S of the operating mechanism, consisting of a pair of side flanges 13, 14 connected by a tubular hub 15, the space thus formed between the flanges being sufficient to receive the required length of raising cord C in spooled-up condition. Of the two flanges named, the flange 14 is, in reality, the most important one, because, when the shade roller R is in proper position, the roller-end and the spool flange 14 are coupled together, so as to rotate in unison, by a mechanism comprising a sheet-metal brake drum D having a peripheral flange 16 whereby the drum, as a unit, is firmly secured to the spool flange 14, as for instance by tabs 17 lanced in the flange 14 and fitting into notches 18 of the drum-flange, the tabs being bent-over or set, as shown at 17a to hold the parts firmly together.

Driving-connection between the brake-drum D and the shade-roller R is established by an extension-prong 19 provided on the edge of the annular brake-flange 20 of the drum and adapted, when the roller R is placed into proper position, to enter the open end of a tubular eyelet 21 forced into the end of roller R, the prong 19 being sufficiently long to permit a small amount of longitudinal floating movement of the roller relative to the prong, without severing their engagement.

From the foregoing it will be understood that this driving-connection between the spool and the roller remains permanent, as long as the roller remains in its regular or operative position; while, on the other hand, the roller may be readily removed from the spool, or the brake-drum specifically, without in any way disturbing the assemblage of the driving mechanism. Furthermore, it will be evident that, when the shade on the roller is pulled down, the roller, thru the intervention of the eyelet 21, becomes the driver to rotate the spool in a clockwise direction, as viewed in Fig. 3, while, when the spool is rotated by a pull on the cord C, the rotation will be in a reverse or anti-clockwise direction, and the shade will, therefore, be raised.

As above stated, this invention has for its particular object the provision of an improved mechanism whereby the tendency of

the weight of the down-hanging portion of the shade to rotate the roller so as to let the shade "run down" by its own weight, will be frictionally resisted, so that it will require an additional hand-pull by the operator to pull the shade down. At the same time, the present device permits not only this slip-frictional action, but the same element or band which causes the holding-friction on the inner face of the brake drum, will be relieved from this comparatively strong frictional engagement, when the drum is rotated reversely, so that, from the practical standpoint, the pull exerted on the cord will have to be just enough to raise the weight of the shade, the friction between the brake-band being then practically negligible.

Referring to Figs. 1 and 2, it will be noted that the base-hub 11 has a bushing 22, the left-hand portion of which is press-fitted into the hub 11, while the right-hand portion thereof extends beyond the hub and is of the same outside diameter so as to serve as an additional bearing for the spool-hub. At its extreme right-hand or outer end, the bushing body is enlarged to overlap annularly the spool-hub and hold the latter in place and against slipping-off sidewise. In addition to this function, the bushing-end has a longitudinally-projecting flange 23 to which the brake-member is anchored.

This brake-band consists of a contact member B made of a resilient strip of sheet metal similar to a part of a clock-spring, one (the inner) end of which is bent to fit into a slot 23a in the bushing-flange 23, to which it may be secured in any suitable manner.

From the bend at the slot 23a the brake band B curves so as to fit snugly against the inside of the brake-drum D, the running-length of the contact between these parts depending upon the requirements of frictional resistance proportionately depending upon the temper and gage of the band. The extreme free and outer end of the brake band B is slightly bent inward, or away from contact with the inner surface of the brake-drum, as at 24, so that, when the brake-drum is rotated clockwise (as viewed in Fig. 3) by the shade on the roller being pulled downward, the frictional contact between the outer end of the band and the drum will push the band into frictional engagement with the inside surface of the drum without cutting the same but, inasmuch as the inner end of the band is anchored on a fixed point, yiz the slot 23a, the rotation of the drum relatively to the band will be considerably impeded, the frictional resistance thus established there being sufficient to counteract any weight of shade on the roller.

Now, when it is desired to raise the shade by a pull on the cord C, the drum will be rotated reversely, or anti-clockwise as viewed in Fig. 3, and therefore, the outer band-end will

be frictionally pulled forward, thus relieving the frictional contact between the main length of the band and the drum, so that the resistance becomes very small, and the operator has to pull on the cord only with sufficient strength to overcome the weight of the down-hanging portion of the shade.

A series of experiments and tests conducted with a view of ascertaining the best form, gage and temper of the brake band, have clearly demonstrated the fact that the anchoring point of the inner end of brake-band should be very near the inner face of the brake-drum, while the outer end of the band should terminate at a point just short of opposite the anchoring-point, and that the flexibility of the band be such that its natural expansion into contact with the drum-flange will be full and even, for its entire running length.

Emphasis is laid upon the fact, that in the present invention the brake-band consists of only one single member which is entirely automatic in its gripping or relieving action, and without requiring any additional or extraneous means or devices to produce the desired results.

In order to hold the brake-band in proper position within the drum, the latter has its outer edge lipped inwardly, as at 16a, just sufficiently to prevent the band from "riding-out" of the drum, and without interfering with the insertion or removal of the band thru the open outer face of the drum.

The entire mechanism is extremely simple and consists of very few parts which can be readily assembled into a marketable unit which is complete and can be attached to the window-casing by one single screw, as is clearly shown in Fig. 1.

There, it will be noted that the bushing which is preferably formed from sheet metal, is drawn shouldered at 22a, near the place where the outside diameters of the base-hub 11 and the bushing co-ordinate to form the bearing for the spool S; while the base-end of the bushing is spun over or headed, as at 22b, so that the bushing becomes a fixed element of the unit. Inasmuch as the bushing-end and the base-hub are both tubular, I take advantage of this fact by using a special screw H the shank portion of which is of regular standard size, while it has a special filister-head, the shoulder of which engages the bushing-shoulder 22a and therefore draws the entire device, comprising the base plate, with all the parts carried by the same, into contact with the window casing, causing the prongs to enter the latter and therefore preventing the base from turning. The outer end of the filister screw head is preferably reduced in diameter and projects forward sufficiently to permit the roller, when the latter is again to be placed in position after removal, to find a centering support-medium,

before the roller-eyelet 21 and tab 19 are brought into engagement.

This center-finding operation is rendered easy by virtue of the fact that the end of the 5 filister-head extension of the screw is rounded so as to readily enter the central hole provided in the roller-end for centering purposes, when the body of the roller is being turned into cylindrical form in the lathe.

10 The assembling of the device is as follows:

1. The spool S and brake-drum D are assembled as a unit, by bending-over flange-tabs 17, by a setting-tool.

15 2. Place the spool-unit S—D onto the base hub, by hand.

3. Press the bushing into place in the base hub 11, and head or spin-over the base-end of the bushing, by spinning-press.

20 4. Insert the brake band B, by placing the inner end into the bushing tab slot 23a and snapping the outer and intervening length into place behind the drum-lip 16a, by hand.

25 Note, that the direction of resistance can be either clockwise or anti-clockwise, in accordance with the way the band is placed.

To install the device on the window casing:

1. Determine position of roller-center.

2. Make a small hole in the casing, in roller-center position (by nail or drill).

3. Make prong-indentations for the base-plate, by using a setting-tool and hammer.

4. Insert filister head screw, by screw-driver.

35 Changes may be made in the construction as well as in the organization of the several parts of the device, without departing from the spirit of the invention.

I claim:

40 1. A mechanism of the character described comprising a stationary support, a member rotatable thereon and having a cylindrical brake-surface, a resilient brake-band frictionally engaging said surface and having its inner end anchored to said support, whereby, when the member is rotated in one direction, frictional resistance will be imparted thereto; and, when said member is rotated in the opposite direction, the frictional resistance will be decreased.

45 2. A mechanism of the character described comprising a stationary support, a brake-drum mounted for rotation thereon, a resilient brake-band having one end anchored to said support and having its other end engaging the inner surface of said drum, and means for rotating said drum in opposite directions.

50 3. A mechanism of the character described comprising a stationary support, a brake-drum mounted for rotation thereon and having an internal brake-surface, a flexible brake-band in engagement therewith and having its inner end anchored to said sup-

port, its other end being free and adapted to conform to the brake-drum surface, and means for rotating said drum in opposite directions.

4. A mechanism of the character described 70 comprising a stationary support having an aperture therethru, a drum having an internal brake-surface, a brake-band in engagement therewith and having one end anchored to the support and having its other end engaging said brake-surface, and means for holding said drum and support together 75 as a unit and secured within said support-aperture.

5. A mechanism of the character described 80 comprising a stationary support having a tubular hub, a spool rotatable on said hub and having an internal brake-drum, a tubular shell secured to said tubular hub and having a flange at its outer end for holding said spool and support against separation, a brake-band anchored at one end to said shell-flange and having its other end in engagement with the inner surface of said brake-drum, and a device passing thru the shell 85 and tubular support, for holding said support, with all the parts carried thereby, on the casing of a window.

6. A mechanism of the character described 90 comprising a stationary support having a 95 tubular hub, a drum rotatable on said hub and having an internal brake-surface, a shell secured in the hub and having a flange for holding the drum and support against separation, a brake-band secured with one end to said shell-flange, and having its other end in engagement with the drum-surface, a device passing thru said shell and hub for holding the support on the casing of a window, and means attached to the drum for coupling 100 the adjacent end of a shade-roller thereto.
